UNITED STATES PATENT OFFICE.

JOSEPH HUSSONG, OF CAMDEN, NEW JERSEY.

DYEING-MACHINE.

No. 895,023.

Specification of Letters Patent

Patented Aug. 4, 1908.

Application filed October 29, 1906. Serial No. 341,037.

To all whom it may concern:

Be it known that I, JOSEPH HUSSONG, a citizen of the United States, residing in Camden, New Jersey, have invented certain 5 Improvements in Dyeing-Machines, of which the following is a specification.

My invention relates to certain improvements in machines for dyeing piece goods and material in bulk, and the invention is 10 particularly adapted for dyeing knit goods such as stockings and like materials.

The main object of my invention is to so construct the machine that the container for the material to be dyed can be readily 15 placed in a vat and removed therefrom, at the same time allowing for the complete circulation of the liquor through the material and for the ready discharge of the material from the container.

20 In the accompanying drawing:—Figure 1, is a longitudinal sectional view of one form of dyeing machine illustrating my invention; Fig. 2, is a sectional view on the line 2—2, Fig. 1, showing the container within 25 the vat; Fig. 3, is a view similar to Fig. 2, showing the container raised clear of the vat and partly turned; Fig. 4, is a detached perspective view of the container; Fig. 5, is a diagram view showing the carrier in relation to the vat and the container inverted, and Fig. 6, is a sectional view of a portion of a metallic vat.

A is a vat of a dyeing machine, in which the liquor is circulated by mechanical means.

35 A' is the dyeing chamber of the machine and A² is the circulating chamber at one end of the vat separated from the dyeing chamber by a fixed vertical partition. In the circulating chamber is a circulating wheel B 40 secured to a vertical shaft B' depending from a frame B² supported on the frame of the vat. This shaft is driven from a power shaft b through gearing b', b², indicated in Fig. 1. There may be two or more of these 45 wheels B if desired, situated side by side, depending upon the width of the vat. The liquor in the vat may be circulated in either direction and the circulation may be reversed at intervals if desired.

50 The above description refers to one form of vat to which my invention is particularly adapted, but it will be understood that my improvement can be applied to other vats as well.

55 D is the container for the material to be dyed. This container is shaped so as to

conform to the shape of the dyeing compartment A' of the vat, giving sufficient clearance so that it can be readily lowered into the vat or removed therefrom. When 60 in the vat as shown in Figs. 1 and 2, it rests on flanges or projections a' at the bottom of the vat. The container is quadrangular in shape and has a perforated bottom d and a perforated top d'. The sides d² and the 65 ends d³ are solid in the present instance. The perforated top section is made in halves in the present instance, as illustrated in Fig. 4, and the sections are hinged at c to the body of the container so that the hinged 70 sections can be thrown back to allow for the charging of the container with the goods to be dyed, or for the ready removal of the goods. I preferably divide the container into a series of compartments by transverse 75 partitions d⁴ which may be either solid or perforated as desired.

E is a frame suspended by chains f, f from a carriage F or any suitable hoisting mechanism common in this class of machines 80 and this frame has side members e, e to which the container D is pivoted. The pivot pins e' project from each end of the container through openings in the arms, illustrated in Fig. 4. Thus the container 85 can be lowered into the vat or raised clear of the vat by simply operating the means for lifting the chains f, f. The container, after it is raised clear of the vat, as illustrated in Fig. 3, may be turned by hand so that the 90 hinged doors can be opened at the side and the goods removed, but I prefer to attach a pin i at one side of the container and suspend a chain I from the carriage F and at the end of this chain is a hook i'. The container is 95 raised to such a point that the pin i can be engaged by the hook i' of the chain and then by lowering the container it will be turned on its pivot. The container is preferably moved to one side of the vat by shifting the 100 carriage on its track f' as illustrated in Fig. 5, and by placing a truck under the container, its contents can be discharged onto the truck by simply turning the container on its pivots until it is reversed as shown.

105 In order to prevent the container turning on its pivots, I may fasten it to the frame by a detachable pin n or other fastening. The operation is as follows:—Each compartment of the container is filled with stockings or 110 other material to be dyed and the hinged sections are closed and secured by any suit-

- able fastenings. The container is then fastened to the frame and lowered into the vat until it rests upon the flanges or projections a' , leaving a clear circulating space between the bottom of the vat and the container, as illustrated in Fig. 1. The circulating wheels are then set in motion and the dye liquor is circulated through the compartments A' , A^2 and through the material in the container.
- 5 The projections or flanges a' close the space between the container and the sides of the vat so that the dye liquor must pass through the container.
- 10 The container being perforated at top and bottom allows for the free circulation of the liquor and allows for a certain movement of the material being dyed, so that all portions of the material will be evenly dyed. After the material is dyed the container is raised
- 15 clear of the vat and shifted to one side and turned over, the pivoted sections or doors open and allow the material to discharge into a receptacle at the side of the vat.
- 20 In Fig. 1, I have shown the vat made of wood and the flanges a' formed by strips secured to the sides, while in Fig. 6, I have shown a metallic vat in which angle irons a^2 are secured to the sides to form the flanges upon which the container rests.
- 25

30 I claim:

1. The combination in a dyeing machine, of a vat, a frame, means for suspending the frame, a container perforated at top and bottom and pivoted to the frame so that it
- 35 can be tilted to discharge the contents, substantially as described.

2. The combination in a dyeing machine, of a vat, a frame, means for suspending the frame, said frame having depending members, a container pivoted to the depending members so as to turn in the frame, the container being perforated at top and bottom, and means for causing the liquor to circulate in the vat and through the container, substantially as described. 45

3. The combination in a dyeing machine, of a vat, a frame, means for suspending the frame, said frame having depending members at each end, a container perforated at top and bottom and having a movable cover, 50 pivot pins at each end of the container adapted to openings in the depending members of the frame, so that when the container is elevated it can be turned on the pivots to discharge the contents, substantially as 55 described.

4. The combination of a dye vat, a frame suspended above the dye vat, a container pivoted to the frame, a pin on the container at one side of the pivot, and a suspended 60 chain arranged to engage the pin so that on the movement of one part in respect to the other the container will be turned on its pivot, substantially as described.

In testimony whereof, I have signed my name to this specification, in the presence of two subscribing witnesses.

JOSEPH HUSSONG.
